UNITED STATES PATENT OFFICE.

CHARLES K. PICKLES, OF ST. LOUIS, MISSOURI, ASSIGNOR TO THE AMERICAN ROLL PAPER COMPANY, OF SAME PLACE.

ROLL-PAPER CUTTER.

SPECIFICATION forming part of Letters Patent No. 423,806, dated March 18, 1890.

Application filed December 3, 1888. Serial No. 292,546. (No model.)

To all whom it may concern:

Be it known that I, CHARLES K. PICKLES, of the city of St. Louis, in the State of Missouri, have invented a certain new and useful Improvement in Roll-Paper Holders and Cutters, of which the following is a full, clear, and exact description, reference being had to the accompanying drawings, forming part of this specification, and in which—

10. Figure I is a front elevation of my improved paper-cutter. Fig. II is an end view.

My invention relates to an improved device for holding and cutting wrapping-paper and the like; and my invention consists in features of novelty hereinafter fully described, and pointed out in the claims.

Referring to the drawings, 1 represents a roll of paper, 2 a cradle in which the roll is placed, and 3 a base to which the cradle is secured. The cradle is so shaped that the roll of paper bears against its inner sides or faces, as shown in Fig. II, and one or both of its upper edges are turned outward, as shown at 4, to form cutting-blades for severing the paper. The inclines of the inner faces are varied, so that the roll will have continuous bearing thereon and a uniform friction or tension, and so that the same amount of force is required to withdraw the paper from the roll, whatever the size of the roll may be—as, for instance, as shown in full lines in Fig. II, the roll of paper has contact with the sides of the cradle at 5. As the roll decreases and becomes of the size shown by dotted line 6, Fig. II, the point of bearing between the roll

and the sides of the cradle shifts to 8. Then as the roll decreases to the size indicated by the dotted line 7 the point of bearing between the cradle and roll is at 10. Then, again, when it decreases to the size indicated by the dotted line 9, the point of bearing between the roll and the sides of the cradle is at 11, and so on until the paper is all removed.

A cradle thus having varied inclines on its inner faces gives to the roll a uniform tension, regardless of the size of the roll.

The paper may be drawn out from either side of the cradle, or but one cutting-edge 4 may be made. If preferred, also, the cutting edge or edges may be slotted, as shown at 12, through which the paper may be threaded and then cut in an upwardly direction.

A paper-cutter thus formed is cheap and durable and requires absolutely no experience to operate it.

I claim as my invention—

1. The roll-cradle having varied inclined inner faces extending in opposite directions and formed with an outturned upper edge 4, providing a cutting-blade for severing the paper, substantially as described.

2. The roll-cradle having varied inclined inner faces extending in opposite directions and formed with an outturned upper edge 4, having a slotted cutting-edge, substantially as described.

CHARLES K. PICKLES.

In presence of—

BENJN. A. KNIGHT,
EDW. S. KNIGHT.
